UNITED STATES PATENT OFFICE.

MORRIS J. GOLDBERG, OF BELLOIT, WISCONSIN, ASSIGNOR TO FAIRBANKS, MORSE & CO.,
OF CHICAGO, ILLINOIS, A CORPORATION OF ILLINOIS.

PRIMING DEVICE.

Application filed September 24, 1923. Serial No. 684,478.

My invention relates to improvements in priming devices for internal combustion engines, and has for its object a device which may be permanently attached to the engine, is easy and simple of operation and simple of manufacture.

My invention will be best understood from the following description and drawing, showing its application to a horizontal engine of the two-cycle type employing crank case compression. Though my invention consists largely in the construction and arrangement of parts hereinafter described and particularly pointed out in the claims, yet I do not limit my invention to the precise form or construction of parts shown or the several parts thereof, inasmuch as various alterations may be made without changing the scope of my invention.

In the drawing Fig. 1 is a view, partly in section, showing a preferred form of my invention; and Fig. 2 is a view of a modified form of my invention which may be used. In the drawings (1) is a cup adapted to hold a small supply of gasoline or other desirable fuel which may be introduced through a hole (2) in the cover or by any other convenient means. In the bottom of this cup is an opening (3) shown closed by needle valve (4), preferably operated by a handle (5) outside. Below the valve control outlet (3) there may be a small passage or chamber (6) vented to the atmosphere by tube (7). In the outlet (8) from chamber (6) is a check valve (9) arranged to prevent pressure or gases passing upward through this opening into chamber (6). Below this check is a tube (10) opening into a larger tube forming a chamber (11). At the lower end of tube (11) is a restriction (12) having a smaller opening (20) through it. This restriction serves the purpose of retaining some retarding material (13) which may be of fibrous material like mineral wool or it may be as indicated in our sketch a piece of flat metal bent up into a spiral shape. Below outlet (20) the passage enters the cylinder at auxiliary fuel supply or priming port (14), this port coming into or in close proximity to the air inlet port (15). Below the check valve (9) there is connected into this passage a pressure equalizing tube or by-pass conduit (16), this being connected also into the scavenging air passage at (17). Pin (21) is

a stop pin preventing the closure of tube (10) by check valve (9).

I may, however, dispense with by-pass (16) and passage (6) and permit the discharge from cup (1) to pass into cup (22) 60 preferably perforated and attached below tube (10) and preferably situated in scavenger passage (15).

When the engine is turned over by hand and starting with the piston in its extreme 65 crank end position (18), as it moves toward the head end it tends to produce a vacuum in the crank case, drawing atmospheric air in through the automatic valve usually provided. This vacuum also extends through 70 the equalizing tube (16), tube (10) and chamber (6). Atmospheric air will, at this time, enter through opening (2) in the cup cover through tube (7) and chamber (6) and will tend to carry any liquid that has 75 dropped through the open needle valve (3) down past the check valve, the tube (10) and through the retardant means (13).

When on the further rotation of the engine the piston returns and crosses opening (14), as in position (19), the pressure which has been developed in the crank case by the crankward movement of the piston will fill the equalizing passage (16) and the vertical passage (11) and (10) up to 85 the check (9), which will be held closed by the pressure. This pressure is sufficient to introduce a charge of air into the cylinder which is then near atmospheric pressure, the exhaust opening being in communication with the atmosphere. The liquid from tube (11), mixed with air, forms an explosive mixture, which on high compression fires very readily. After the engine is started, the priming device may be cut out 90 in the manner shown or in any other suitable manner.

By locating the auxiliary port 14 in the cylinder wall of the engine into or in close proximity to the air port 15 it will be seen 100 that I have provided means for preventing fuel from being sucked back into the crank case of the engine. The port 14 will be evidently uncovered for only a very short part of the beginning of the upward 105 stroke of the piston and very little of the gases in the cylinder will be sucked back through the chamber 11, because the port is only open for a short interval of time and only when the crank 110

case suction is at a minimum and practically negligible. Fuel is further prevented from entering the crank case by the use of tube 10, which projects past the opening of conduit 16 and down into chamber 11. While I show chamber 11, it is evident this chamber may be omitted and that the by-pass conduit 16 may be formed in a continuous piece so as to connect with priming port 14. 10 It is evident that while I describe my device as being applied to an internal combustion engine for priming purposes it may be employed in such an engine in any case where an auxiliary fuel feed device is advantageous. For example, under certain conditions, particularly at no-load, it is difficult to keep an engine running efficiently on the heavier hydro-carbons, due to the lowering in temperature of cylinder walls, combustion chamber, etc. In such a case my device could be employed with efficiency and economy as an auxiliary fuel feeding device for idling purposes. I do not wish to be limited in the application of my device, therefore, to priming purposes only.

I claim:

1. In an auxiliary fuel feed device adapted to be applied to an internal combustion engine having crank case compression, a by-pass conduit comprising means limiting the flow of fuel into the crank case, one end of the conduit being in direct communication with a cylinder of the engine and the other end in communication with a scavenging passage of the engine, said conduit being adapted thereby, to utilize suction in said passage for fuel intake to said conduit, and to utilize pressure in said passage for expelling the fuel to the cylinder.
2. In an auxiliary fuel feed device adapted to be applied to an internal combustion engine having crank case compression, a by-pass conduit adapted to deliver an auxiliary fuel, and comprising means for limiting the flow thereof to the crank case, one end of the conduit being in direct communication with a cylinder of the engine and the other end in communication with the scavenging conduit of the engine, and means adapted to utilize a suction in said scavenging conduit for supplying fuel to said by-pass conduit.
3. In an auxiliary fuel feed device adapted to be applied to an internal combustion engine having crank case compression, a by-pass conduit having one end terminating in a cylinder of the engine and the other end in communication with the scavenging air passage of the engine, means adapted to utilize a partial vacuum in said passage for supplying fuel to said by-pass conduit, and fuel retarding means in said by-pass conduit, the conduit being so constructed and disposed as to limit the flow of fuel to the crank case.
4. In an auxiliary fuel feed device adapted to be applied to an internal combustion

engine having crank case compression, a by-pass conduit having one end in communication with a port in the cylinder of said engine and the other end in communication with the scavenging passage of the engine, whereby a suction in said passage is utilized to deliver fuel to said conduit, and means for limiting the flow of fuel into the crank case.

5. In an auxiliary fuel feed device adapted to be applied to an internal combustion engine having crank case compression, a by-pass conduit having one end adapted to be placed in communication with a port in the cylinder of said engine and the other end adapted to be placed in communication with the crank case of the engine, means for supplying fuel to said conduit whereby fuel may be drawn into said conduit by crank case suction and driven out of said conduit into said cylinder by crank case pressure, and means for limiting the flow of fuel into the crank case.

6. In a gas engine, a by-pass conduit in communication with the crank case and entering the cylinder between the scavenging port and the head end of the cylinder, an auxiliary fuel supply adapted to augment the main fuel supply during priming and light-load operation of the engine, the auxiliary fuel being introduced to said by-pass conduit by crank case suction, and a valve controlling said fuel supply, the fuel supply connection and conduit being so disposed as to limit the flow of fuel into the crank case.

7. In a gas engine having a by-pass conduit in communication with the crank case and entering the cylinder between the scavenging port and the head end of the cylinder, a fuel supply connected to said by-pass conduit, a valve controlling said fuel supply, said valve being adapted to be actuated by crank case suction to deliver fuel to said conduit, and means associated with the fuel supply and conduit for preventing the flow of fuel into the crank case.

8. In a priming device, a by-pass conduit in communication with the crank case of an engine and connected to the cylinder of the engine between the scavenging port and the head end of the cylinder, a fuel supply means operative under the influence of a periodic crank case suction, fuel retarding means, means for limiting the flow of fuel back to the crank case, and a valve controlling the admission of fuel into the by-pass.

9. In combination with an auxiliary fuel feed device adapted to augment the normal running fuel supply for an internal combustion engine, a cylinder having an auxiliary fuel port therein, a piston adapted to open and close said port, a scavenging air passage, a by-pass conduit between said passage and said port, and a fuel supply in said conduit, comprising means retaining the fuel from

the scavenging air passage, said conduit being adapted to receive a fuel charge under influence of a periodic suction in said air passage, and adapted to utilize a pressure 5 in said passage to expel the fuel from said conduit to the cylinder.

10. In combination with an auxiliary fuel feed device for an internal combustion engine, a cylinder having an auxiliary priming port therein, a crank case, a piston adapted to open and close the port, a by-pass conduit between the port and the crank case, means for introducing a priming fuel 15 in said conduit, and a tortuous passage for the fuel, through a portion of said conduit.

11. In combination with an auxiliary fuel feed device for an internal combustion engine, a cylinder having an auxiliary priming port therein, a crank case, a piston adapting port to open and close the port, a by-pass conduit between the port and the crank case, and valve controlled means for supplying 20 fuel to said conduit by crank case suction.

12. An auxiliary fuel feed device adapted 25 to be removably positioned in the scavenging

air passage of an internal combustion engine, comprising a body having a fuel passage-way therein, and a spiral fuel distributing surface adapted to be positioned in the line of flow of the scavenging air, the fuel passage-way being so disposed and connected with the engine as to limit the flow of the fuel to the crank case through the scavenging air 30 passage.

13. An auxiliary fuel feed device adapted 35 to be removably connected to a priming port adjacent the scavenging air passage of an internal combustion engine, comprising a member having a fuel passage therein, a valve in said fuel passage, and a fuel distributing surface, the fuel feed device being adapted to divert a portion of the scavenging air under pressure for introducing a priming fuel for light-load operation of the 40 engine, to augment the normal running fuel, and the device being further adapted to receive a charge of the priming fuel under influence of a periodic crank case suction. 45

MORRIS J. GOLDBERG.
